ABSTRACT OF THE DISCLOSURE

An air swept coal pulverizer and classifier adapted for rapid response to the demands of a steam generator. The classifier receives air within entrained coal particles from the pulverizer, separates the coarse from the fine coal particles entrained in the air, allows the fine particles to pass to the steam generator and returns the coarse particles to the pulverizer. Coal feeders to the pulverizer are responsive to a control signal indicating the coal feed requirements of the steam generator. The classifier is temporarily adjusted to decrease the quantity rejection of coarse particles in response to the rate of change of an increasing control signal. Air flow through the pulverizer may also be increased in response to the rate of change to this increasing control signal.

BACKGROUND OF THE INVENTION

This invention relates to the application of a coal pulverizer to the firing of a steam generator and in particular to an apparatus for improving the response time of coal supply to the steam generator in response to a change in demand for coal feed.

Large steam generators are commonly fired with pulverized coal by what is called the direct firing system. Crushed coal is fed into a pulverizer as required by the steam generator with the coal then being pulverized and immediately supplied directly to the steam generator. The change in firing rate to the steam generator is controlled by regulating the rate of coal feed to the pulverizer.

The pulverized coal particles are swept from the pulverizer by a flow of gas, such as air. This gas stream along with the entrained coal particles are passed through a classifier which separates the fine particles of coal from the coarse particles. The coarse particles are returned to the pulverizer for further grinding while the fine particles are conveyed with the gas stream to the steam generator furnace. These classifier settings are generally manually adjustable so that they may be set for the proper coal fineness for the best over-all operation. If the coal passing to the furnace is too coarse, combustion is delayed and particles of coal are incompletely burned resulting in an unburned carbon loss which lowers the steam generator efficiency. If on the other hand, the coal is too finely ground, this results in excessive power consumption by the pulverizer and excessive wear. The classifier settings are therefore adjusted for a desired coal fineness and readjusted only when required due to wear of pulverizer and classifier parts or by a change in the type of coal being fired.

Steam generators when operating in conjunction with turbo generators are frequently required to make rapid load changes while maintaining parameters such as temperature and pressure at a stable level. Delay in the reaction time of inputs to the steam generator, such as fuel feed, increase the difficulty of rapid response to load changes and limit the rate at which a load change can safely be made.

When a change in fuel feed is required for a steam generator, the rate of feed to the pulverizer is changed.

2

There is no significant change in the output from the pulverizer until about a minute later. In order for the pulverizer to grind coal at the increased rate, there must be a larger quantity of coal within the pulverizer itself and therefore the output rate is not increased until the coal storage within the pulverizer has increased to a new level. It is known that the rate of grinding of a pulverizer is a function of the fineness to which the coal must be ground as well as the amount of coal which is inside the pulverizer within reasonable operating limits.

Some attempt to increase the response of coal delivery from the pulverizer has been made in the past by changing the air flow through the pulverizer simultaneously with the increase in coal feed. The range of air flow available is limited since too low an air flow will permit coal settling in the horizontal runs of pipe while too high an air velocity may cause the flame in the furnace to move so far from the burner as to permit a loss of the fires. While the increase in air flow through the pulverizer will operate to increase the amount of coal entrained in the air stream, there is also an increase in the air velocity passing through the classifier and so the dynamic forces increase, resulting in a rejection of most of the coarse particles which have been entrained due to the increased air flow. The gain due to this air flow therefore is minimal.

SUMMARY OF THE INVENTION

An adjustable coal classifier is supplied between a pulverizer and a steam generator furnace. This classifier is adjusted in response to the steam generator fuel feed demand signal in addition to the conventional response wherein fuel feed to the pulverizer is adjusted. This provides an immediate increase in the delivery of coal to the furnace since the classifier is adjusted to permit the passage of coarser coal particles. This takes coal from the amount which would otherwise be returned to the pulverizer. The pulverizer will also sustain a higher grinding rate for the coarser requirements established by the new classifier setting so that delivery from the pulverizer can be sustained at a higher rate consistent with the increased fuel feed to the pulverizer. The classifying means are then gradually returned to the original position to provide for the delivery of coal of the proper fineness to the furnace. During this time period the coal storage within the pulverizer can be built up to maintain the higher grinding rate at normal fineness.

Conversely, on the decrease in demand, the classifier is adjusted to reject more coal, permitting a similar and immediate response in the load decrease direction. While variation in fineness to the furnace will result in a high unburned carbon loss for a load increase and higher power consumption for a load decrease, these are only temporary conditions and are insignificant compared to the increased ability to rapidly control the steam generating system.

The air flow through the pulverizer may be simultaneously increased to increase the amount of coal picked up from the pulverizer. The change in classifier setting permits the increased coal picked up by this air flow to be passed on to the steam generator for immediate load response.

BRIEF DESCRIPTION OF THE DRAWINGS

FIGURE 1 is a schematic diagram of a steam generator and turbo generator combination showing the control system for regulating the coal pulverizing and feeding apparatus;

FIGURE 2 is a sectional side elevation of the coal pulverizer and classifier; and

FIGURE 3 is a plan view of the pulverizer and classifier indicating the mechanism for simultaneously adjusting the classifier settings.

DESCRIPTION OF THE PREFERRED
EMBODIMENT

Steam generator 2 has a furnace 3 fired by burners 4. The steam generator has tubular heating surface 5 through which water to be evaporated is forced by feed pump 7 and controlled by feedwater valve 8. Steam line 9 conveys the steam to the turbine 10 through the turbine throttle valve 12. The turbine is directly connected to an electric generator 13 with a watt meter 14 measuring the electrical output of the system.

A flow of secondary air 15 is supplied through air control dampers 17 to support combustion in the furnace. A flow of primary air 18 is forced by fan 19 through the pulverizer 20, classifier 22 and the control damper 23 through coal pipe 21 to the burners 4. This air entrains coal from pulverizer 20 and conveys it to the furnace 3. A supply of coal 24 is fed by coal feeder 25 to pulverizer 20 at a rate which during steady state operation is identical with the coal feed requirements of the steam generator. This crushed coal is pulverized to a fine powder in pulverizer 20 and conveyed by the primary air flow 18 to the classifier 22. The fine coal is passed through the classifier to the furnace while the coarser particles are rejected and returned through line 27 to the pulverizer for further grinding.

A signal indicating the actual generator output is passed through control line 28 to set point 29 where it is compared with a desired generation signal 30. A fuel demand signal is passed through control line 32 with the signal being at a level to indicate any change in fuel input required to the steam generator. Other control signals (not shown) are used to regulate the feedwater flow to the steam generator as well as to the turbine throttle valve position. Since this invention deals with fuel feed to the steam generator, these other control signals are not considered. The illustration in FIGURE 1 is that of a once-through steam generator which is the type in which rapid control response is particularly essential. If this system were used on a drum type steam generator, the primary fuel feed signal would normally come from boiler pressure rather than generator output.

This control signal is then modified by control element 33 which incorporates proportional, integrating, and differential action into the control signal to an extent required for the particular characteristics of the steam generator and turbine systems. This modified fuel demand signal then passes through control line 34 with identical signals being passed through control lines 35 to air flow controller 36 and control lines 37 and 38 to coal feeder controller 39. Since the air fuel ratio must be maintained approximately constant, the secondary air flow is adjusted in proportion to the fuel feed. Controller 36 operates to physically move dampers 17 regulating the flow of primary air 15 while controller 39 operates to adjust the speed of coal feeder 25 regulating the rate of introduction of coal 24 to the pulverizer 20. When air control damper 17 is adjusted, there is very little delay in the change of air flow to the steam generator. The only delay is due to acceleration of the air, compression of the air where pressure must change, and for certain types of control the inertia of a fan where its speed must be changed. There is however substantial delay between the time that the rate of feed of coal through feeder 25 is changed and the time at which this increased coal feed is reflected on the delivery rate of coal through coal pipe 21 to the furnace. While there is some transport time delay involved, the most significant delay is that required to increase the coal storage in the pulverizer to a point which attains equilibrium at the new higher grinding rate.

In order to eliminate or diminish this delay, the fuel feed demand signal is simultaneously passed through control line 40 to control element 42 where it is modified with derivative action. This derivative action, which is commonly called rate action, produces a signal which is

indicative of the rate of change of the control signal; and this rate action signal is passed through control line 43 to classifier controller 44. This control signal operates to adjust the classifier setting simultaneously with any change in coal feeder speed. The change in the classifier setting is a function of the rate of change of the coal feeder speed, with the control signal through control line 43 decreasing slowly when there is no change in the rate of feeder speed, so the setting of classifier 22 returns to its original setting slowly during stable operation.

FIGURE 2 illustrates a typical pulverizer wherein coal is fed through pipe 42 into a rotating bowl 53. The coal introduced into this bowl is crushed between a stationary but rotating roller 54 to effect pulverization. A gas such as secondary air is supplied underneath the bowl through an opening 55 and passes upwardly through annular spaces 57 sweeping fine coal from the outer edges of the rotating bowl 53 and entraining it in the air flow. This air along with the entrained coal particles is passed upwardly to the classifier 22 and must flow radially inward through openings 58. Adjustable vanes 59 impart a rotating motion to the air flow which must pass around deflector ring 60 and upwardly through the air outlet 62. While the fine particles entrained in the air stream are able to remain entrained while the air flow makes these changes in direction, the coarser particles are thrown outwardly and downwardly being returned through an opening 63 to the rotating bowl 53.

Adjusting arms 64 are directly connected to the adjustable vanes 59 so that the vanes may be adjusted to regulate the speed of rotation of the air flowing through the pulverizer. When the vanes are adjusted closer to the radial position, there is decreased spin, and a higher percentage of the coarse particles are passed through the classifier. Conversely as the vanes approach a tangential position, this spin is increased with an increased rejection of the coal through opening 63.

A ring linkage 65 engages all of the adjusting arms 64 so that they may be moved simultaneously. Classifier controller 44 operates on this ring linkage to adjust the position of classifier vanes 59. As previously described, an increased coal demand signal not only operates on controller 39 to increase the coal feeder speed, but also sends a control signal through control line 40 and a rate signal through control line 43 to controller 44. This controller 44 then rotates control linkage 65 to the left so as to move the control vanes 59 closer to the radial position. This immediately decreases the amount of coal rejected by classifier 22, thereby increasing the amount of coal passing through outlet 62 and decreasing the amount of coal being returned through opening 63. Instant response is therefore obtained in fuel flow to the furnace without an increase in coal storage in bowl 53 which would be required to sustain the higher grinding rate at normal fineness. Since the pulverizer during this time is required to grind less finely, the increased feed rate can be sustained. Since it is undesirable to continuously operate the steam generator with unnecessarily coarse coal, the adjustable vanes 59 are allowed to slowly drift back to the original position with coal storage in the rotating bowl 53 being increased during this time period.

While the adjustment of the classifier adjustable vanes accomplish an increase in pulverizer response, an even better response can be obtained by simultaneously and temporarily adjusting the flow of primary air through the pulverizer. This is accomplished by regulating the air control damper 23 which may be located either downstream of the pulverizer or upstream of the pulverizer where it need handle only clean air. To accomplish this the rate signal passing through control line 43 is also passed through control line 67 to primary air flow controller 68 which operates to increase the primary air flow through the pulverizer temporarily when there is a demand for coal flow increase to the steam generator. This increases the air flow velocities within the pulverizer

20 thereby entraining more pulverized coal in the air flow. While the increased air velocity through the classifier 22 would normally reject a very large percentage of the increased amount of coal entrained, in combination with the previously described adjustment of the classifier adjustable vanes 59, this increased supply of coal is enabled to remain entrained in the air. The increased coal supply is therefore immediately conveyed to the furnace for rapid response to a required load change.

The description of the preferred embodiment has considered an increase in coal demand to the furnace. Increased response to a load decrease requirement is also obtained by the apparatus of my invention. The adjustable vanes 59 are moved in the opposite direction so as to increase the amount of rejection and return to the bowl 53 at the same time that there is a decrease in the speed of the coal feeder 25. This permits the bowl 53 to gradually decrease the storage of coal therein while the adjustable vanes 59 slowly return to their original position.

While I have illustrated and described a preferred embodiment of my invention it is to be understood that such is merely illustrative and not restrictive and that variations and modifications may be made therein without departing from the spirit and scope of the invention. I therefore do not wish to be limited to the precise details set forth but desire to avail myself of such changes as fall within the purview of my invention.

What I claim is:

1. An apparatus for supplying pulverized coal to a steam generator furnace comprising: a coal pulverizing means; adjustable feed means for supplying coal to said pulverizer at a first rate; means for establishing a flow of gas through said pulverizing means and to the furnace, said gas flow entraining particles of coal within said pulverizer and conveying them to the furnace; adjustable classifying means for separating coarse particles from the coal particles entrained in said gas flow, located intermediate said pulverizing means and said furnace; means for returning the coarse particles to said pulverizer; means for establishing a control signal indicative of a desired fuel feed input to the steam generator furnace; and means for adjusting said feed means to a second rate in response to said control signal; means for simultaneously adjusting said classifying means in response to said control signal, in a direction to increase the coarseness of particles returning to said pulverizer in response to a control signal indicating an increased desired fuel feed input.

2. An apparatus as in claim 1 wherein said means for adjusting said classifying means in response to said control signal also comprises: means for adjusting said classifying means in such a direction as to decrease the coarseness of particles returned to said pulverizer in response to a control signal indicating a decreased desired fuel feed input.

3. An apparatus as in claim 1 having a modified control signal which is the derivative action of said control signal; and wherein said means for adjusting said classifying means operates in response to said modified control signal.

4. An apparatus as in claim 3 wherein said means for adjusting said classifying means in response to said modified control signal comprises: means for adjusting

said classifying means in a direction to decrease the coarseness of particles returned to said pulverizing means in response to the modified control signal indicative of a decreased desired fuel feed input.

5. An apparatus as in claim 3 having also means for returning said classifying means to the original position during a predetermined time period.

6. An apparatus as in claim 5 wherein said means for adjusting said classifying means in response to said modified control signal comprises: means for adjusting said classifying means in a direction to decrease the coarseness of particles returned to said pulverizing means in response to the modified control signal indicative of a decreased desired fuel feed input.

10 7. An apparatus as in claim 1 having also: regulating means for regulating the gas flow through said pulverizer means; and means for simultaneously adjusting said gas flow regulating means in a direction to increase the gas flow in response to a control signal indicating an increased desired fuel feed input.

15 8. An apparatus as in claim 2 having also: regulating means for regulating the gas flow through said pulverizer means; means for simultaneously adjusting said gas flow regulating means in a direction to increase the gas flow in response to a control signal indicating an increased desired fuel feed input; and means for adjusting said gas flow regulating means in such a direction as to decrease the gas flow in response to a control signal indicating a desired decreased fuel feed input.

20 9. An apparatus as in claim 3 having also: regulating means for regulating the gas flow through said pulverizer means; and means for adjusting said gas flow regulating means in response to said modified control signal.

25 10. An apparatus as in claim 4 having also: regulating means for regulating the gas flow through said pulverizer means; means for regulating said gas flow in such a direction as to increase the gas flow in response to a modified control signal indicating an increased desired fuel feed input; and a means for adjusting said gas flow regulating means in such a direction as to decrease the gas flow in response to a modified control signal indicative of a decreased desired fuel feed input.

30 11. An apparatus as in claim 9 having also: means for returning said classifying means to the original position during a predetermined time period; and means for returning said gas flow regulating means to a position corresponding with the original gas flow rate during a predetermined time period.

35 12. An apparatus as in claim 10 having also: means for returning said classifying means to the original position during a predetermined time period; and means for returning said gas flow regulating means to a position corresponding with the original gas flow rate during a predetermined time period.
